titles of books.

A decorative banner at the top of the page. It features a stylized illustration of a building with multiple windows and a decorative roofline. To the right of the building, the word "Invention" is written in a cursive script. Below the building, the name "Thomas M. Feely, Esq." is written in a larger, bold, serif font. The entire banner is set against a light background.

UNITED STATES PATENT OFFICE.

THOMAS McFEELY, OF PHILADELPHIA, PENNSYLVANIA.

BUILDING CONSTRUCTION.

943,447.

Specification of Letters Patent. Patented Dec. 14, 1909.

Application filed February 24, 1908. Serial No. 417,468.

To all whom it may concern:

Be it known that I, THOMAS McFEELY, a citizen of the United States, residing in Philadelphia, Pennsylvania, have invented 5 certain Improvements in Building Construction, of which the following is a specification.

My invention relates to buildings which may be employed as hotel, hospital, factory 10 or office structures; and the object of my invention is to provide in such a building the maximum amount of light and ventilation.

When designed as a hotel for use at the seashore or for any other point where the 15 landscape is of an attractive character and disposed at right angles to the longitudinal position the building should occupy, every room of said building shall have windows permitting a view of said landscape or the 20 sea, as the case may be, and during some part of the day will receive direct sunlight. The building is particularly applicable for seashore resorts.

A further and important feature of my 25 invention is the provision for efficient ventilation of all parts of the building; the arrangement being such that breezes from any quarter are directed to every room.

My invention is fully shown in the accompanying drawings, in which:

Figure 1, is a front elevation of a building made in accordance with my invention; Fig. 2, is a side elevation of the same; Fig. 3, is a sectional plan view, taken on the line 35 *a—a* Fig. 1; Fig. 4, is a sectional view, taken on the line *b—b*; Fig. 3, and Fig. 5, is a sectional perspective view illustrating a detail of my invention.

The first or ground floor of the building 40 structure forming the subject of my invention may be of ordinary quadrilateral construction, preferably rectangular; but depending always upon the shape of the lot and its position with respect to other structures and the objective points of the landscape or sea. In general, however, I prefer that the building shall be rectangular and at least twice the length of its width; any greater length being entirely practicable so 45 long as proportions necessary for stability are maintained.

Above the first floor, indicated at 1, instead of having a solid construction, I provide a series of substantially detached buildings, indicated at 2, which are joined to a 50 central structure 3 providing a main hall 4

running the full length of the building, which hall communicates with the semi-detached structures 2 above the first floor, and with air spaces 5 between said structures. 60

Each of the semi-detached structures which extend above the first floor has a hall 6 running its length, which halls communicate at one end with a central hall 4 running 65 the length of the building, and with fire escapes 7 at the outer ends. On opposite sides of these short halls 6, rooms 8 are disposed in said semi-detached structures, and these rooms have windows opening into the 70 air spaces 5. The semi-detached buildings are constructed at such an angle with respect to the contour of the whole structure that by providing each of said rooms with bay windows of special shape such as those indicated 75 at 9, every room of the building is provided with a view of the ocean or the landscape, as the case may be, and will receive during some part of the day, direct sunlight.

The main hall 4 has windows 10 which 80 open toward the air spaces, and by this means ventilation of the entire building is readily and easily provided for. In order that air may freely pass from one side of the building to the other when the windows 85 10 of the hall 4 are closed, I provide communicating passages 11 for the air spaces 5 between the ceiling of one story and the floor of the next story. These passages may be kept open at all times and by this arrangement 90 complete ventilation of the several rooms of the structure is assured, with the enjoyment of breezes blowing from any quarter. If desired, the central hall may be wholly open between the air spaces, with 95 doors leading to the same on opposite sides of said air spaces. The building is equipped with all of the necessary details incident to modern life, such as the convenience of sanitary plumbing, fire escapes 7, elevators 12, 100 stairways 13, &c.

At the rear of the structure, triangular buildings 14 may be provided, which serve, in the one instance of accommodating a chimney 15, ventilating stack 16, cables, 105 water and steam pipes, and other necessary elements leading to the several floors, and in the other instance of providing a shaft for elevator service to the top of the building where a large room or roof garden 20 110 may be provided by covering over the air spaces 5, preferably with glass. The latter

triangular building may also carry a ventilating stack 16, as well as pipes and cables.

At the front and above the first floor of the building, when used as an hotel, a sun 5 parlor may be provided, indicated at 25, preferably with a glass roof, and this sun parlor may or may not be inclosed at the front, as desired.

I claim:

10 1. A building comprising a rectangular base, a series of semi-detached structures surmounting said base and disposed diagonally with respect to the general contour of the same, said semi-detached structures 15 paralleling each other, and an intermediate structure having walls paralleling the base to which said semi-detached structures are connected and with which they communicate, the arrangement of said structures 20 providing air spaces or courts between the same.

2. A building comprising a series of semi-detached structures disposed diagonally and paralleling each other, an intermediate 25 structure having parallel walls to which the semi-detached portions are connected and with which they communicate, the arrangement of said structures providing air spaces or courts between the same, and provision 30 for communication between opposite air spaces through said intermediate structure.

3. A building comprising a rectangular base, a series of semi-detached structures surmounting said base and disposed diagonally with respect to the general contour of the same, said semi-detached structures paralleling each other, and an intermediate structure having walls paralleling the base to which said semi-detached structures are 40 connected and with which they communicate, the arrangement of said structures providing air spaces or courts between the same, and provision for communication between opposite air spaces through said intermediate 45 structure.

4. A building having a rectangular base structure, a series of semi-detached structures above said base structure and disposed diagonally with respect to the same, 50 the arrangement of said structures providing air spaces or courts between the same, and an intermediate structure having walls paralleling the base to which said semi-detached structures are connected on opposite 55 sides.

5. A building having a central rectangular structure with parallel walls, diagonally disposed semi-detached portions connected to and extending from opposite sides of said 60 rectangular structure and providing air spaces between the same, rooms in said diagonally disposed portions, and bay windows arranged in said rooms whereby the view in front of said building may be seen 65 from each of said rooms.

6. A building having a centrally disposed semi-detached portion, a hall or corridor portion with parallel walls disposed on opposite sides of the hall or corridor portion and communicating with the same, the arrangement 70 of the latter providing air spaces or courts between the same, and provision for communication between said air spaces through the connecting hall or corridor portion.

7. A building having two sets of diagonally disposed portions semi-detached, an intermediate hall or corridor portion centrally disposed with respect to the semi-detached portions of the structure and communicating therewith, the arrangement of 80 the semi-detached portions providing air spaces or courts between the same, and provision for communication between said air spaces through the connecting hall or corridor portion. 85

8. The combination of a building having a base structure, a central rectangular portion extending the full length of said building and providing halls at the several 90 stories, semi-detached portions above said base structure communicating with the central rectangular portion, the arrangement of said semi-detached portions providing air spaces or courts between the same, and floors 95 for the several stories of the building, said floors having horizontal openings extending between said air spaces or courts, said openings providing for the passage of air between said courts. 100

9. The combination of a building having a base structure, a central rectangular portion extending the full length of said building and providing halls at the several stories, diagonally disposed semi-detached 105 portions above said base structure communicating with the central rectangular portion, the arrangement of said semi-detached portions providing air spaces or courts between the same, and floors for the several stories 110 of the building, said floors having horizontal 115 openings extending between said air spaces or courts, said openings providing for the passage of air between said courts. 120

10. A building having semi-detached portions with halls extending longitudinally of 115 said portions, a main longitudinal hall or corridor portion centrally disposed with respect to the whole structure and communicating with the halls of said semi-detached portions which are arranged on opposite 120 sides of said main hall portion, the disposal of the latter providing air spaces between the sections, rooms in said detached portion communicating with the halls of the same, bay windows arranged in said rooms where by objects in front of the building may be viewed from each room, and means providing communication with the air spaces through the main hall or corridor portion of 125 the building. 130

11. A building having semi-detached diagonally disposed portions with halls extending longitudinally of said portions, a longitudinal main hall or corridor portion 5 centrally disposed with respect to the whole structure and communicating with the halls of said semi-detached portions which are arranged on opposite sides of said main hall portion, the disposal of the latter providing 10 air spaces between the sections, rooms in said detached portion communicating with the halls of the same, bay windows arranged in said rooms whereby objects in front of the building may be viewed from each room, 15 and means providing communication with the air spaces through the main hall or corridor portion of the building.
12. A building having semi-detached por-

tions diagonally disposed, and a main rectangular portion centrally disposed with respect to the whole structure and providing a hall or corridor affording communication between the semi-detached portions, the latter paralleling each other and providing air spaces between them, and windows disposed 20 in the hall portion and providing direct communication with the air spaces on opposite sides of the same.

In testimony whereof, I have signed my name to this specification, in the presence of 25 two subscribing witnesses.

THOMAS McFEELY.
